UNITED STATES PATENT OFFICE.

EZEKIEL EDGERTON AND ELMER W. EDGERTON, OF CLEVELAND, OHIO.

SPRING-BED.

SPECIFICATION forming part of Letters Patent No. 375,141, dated December 20, 1887.

Application filed September 30, 1887. Serial No. 251,095. (No model.)

To all whom it may concern:

Be it known that we, EZEKIEL EDGERTON and ELMER W. EDGERTON, both of Cleveland, in the county of Cuyahoga and State of Ohio, 5 have invented certain new and useful Improvements in Spring-Beds, of which the following is a specification.

This invention relates to spring-beds; and it consists in the peculiar construction and combination of the parts, as hereinafter described, and pointed out in the claim.

In the accompanying drawings, Figure 1 is a top or plan view showing a portion of the woven-wire top broken away. Fig. 2 is a side 15 elevation of the whole spring-bed.

A A are a series of longitudinal wooden slats joined at each end and near their middle by cross-slats B B, which cross-slats support the whole structure in the bedstead.

20 C C are volute springs attached to the slats A A and are joined together at their tops by cross-wires c c.

D is a woven-wire fabric secured at each end to clamp-bars E E, and lies on the top of said 25 springs C C.

F F are brace-slats attached to the middle cross-slat B, their ends being secured to the bars E E.

G G are strong brace-wires having loops at their upper corners which are attached to the 30 springs at the sides of the bed, their lower ends being secured to the slats F F.

The objects of this combination are to provide against the stretching and sagging of the woven-wire fabric, the springs C C supporting 35 it against any undue strain and the brace-slats F F serving to prevent the end bars approaching each other, on the other hand they serve to distend them, and thus preserve the woven-wire fabric intact, and the side braces, G G, 40 serving to keep the sides of the woven-wire fabric stretched.

Having described our invention, we claim as follows:

The brace-wires G G, having the loops attached to the springs C C at the sides, their lower ends secured to the slats F F, in combination with the woven-wire fabric D and the supporting slats and frame A B E, as shown 45 and described.

EZEKIEL EDGERTON.
